(57) **CLAIM**

The ornamental design for a surgical kit for percutaneous endoscopic gastrostomy procedures, as shown and described.

DESCRIPTION

FIG. 1 is a perspective view of the embodiment of the new surgical kit according to the invention.

FIG. 2 is a top plan view of the embodiment of the surgical kit depicted in FIG. 1.

FIG. 3 is a side plan view of the right-hand longer side of the embodiment of the surgical kit depicted in FIG. 2 with the open top surface of the kit facing left.

FIG. 4 is a side plan view of the lower shorter side of the embodiment of the surgical kit depicted in FIG. 2 with the open top surface of the kit facing up.

FIG. 5 is a side plan view of the upper shorter side of the embodiment of the surgical kit depicted in FIG. 2 with the open top surface of the kit facing up.

FIG. 6 is a bottom plan view of the embodiment of the surgical kit depicted in FIG. 2; and,

FIG. 7 is a side plan view of the left-hand side longer side of the embodiment of the surgical kit depicted in FIG. 2.
